WELL PERFORATOR SHAPED CHARGE

Will H. Lindsay, Jr., Fullerton, Calif., assignor to Borg-Warner Corporation, Chicago, Ill., a corporation of Illinois

Continuation of application Serial No. 276,156, March 12, 1952. This application December 18, 1957, Serial No. 703,670

4 Claims. (Cl. 102—20)

This invention relates generally to well perforators and more particularly to improvements in explosive shaped charges for perforating well casings and the surrounding earth formations in well boreholes. This application is a continuation of my copending application Serial No. 276,156, filed March 12, 1952, for "Well Perforator Shaped Charge," now abandoned.

In the employment of a plurality of shaped charges for making a plurality of perforations through fluid-filled well casings and into the surrounding formations, it has become accepted practice to mount the shaped charges adjacent one another inside suitable fluid-tight, thick walled, cylindrical, steel housings, which are adapted to be lowered into the fluid-containing well boreholes to be perforated. In such apparatus, the shaped charges are usually positioned at suitable, longitudinally spaced intervals along the length of the interior bore of the housing, with the perforating axes of the shaped charges directed laterally thereof in alignment with suitable ports formed in the housing walls, the ports being initially closed prior to firing of the shaped charges by suitable, relatively thin, frangible, fluid-tight port seals. Upon firing of the shaped charges, the port seals are perforated, destroyed, or otherwise removed by the shaped charge perforating jets which continue on through the casing and into the surrounding formations. The cylindrical housing serves initially to confine therein the blast of the shaped charges other than that directed into the perforating jets.

It has been discovered that when shaped charges of the type heretofore employed are detonated together or nearly simultaneously within the cylindrical housing containing them, the explosive forces of the several charges react upon one another in manners unfavorable to the proper detonation and formation of the most perfect and efficient perforating jets. This interference between shaped charges is thus, at the same time, both the cause and the result of the inefficient utilization and direction of the explosive forces of the shaped charges.

It is therefore an object of this invention to provide a shaped charge perforating device of increased penetrating efficiency.

It is another object of this invention to provide a shaped charge perforating unit having increased penetrating power for a given overall size.

It is a further object of this invention to provide a shaped charge unit of superior design whereby the perforating jet is of more effective shape and power.

It is a still further object of this invention to provide a shaped charge construction which more efficiently utilizes and directs the explosive forces thereof to produce a perforating jet of superior penetrating force.

It is a still further object of this invention to provide a shaped charge unit, the character and action of which is less susceptible to interference by the firing of adjacent shaped charges.

It is a still further object of the invention to provide a shaped charge unit, the action of which when fired causes

2

less interference with the firing action of other adjacent shaped charges.

It is a still further object of this invention to provide shaped charge units which are more suitable to substantially simultaneous firing in relatively close proximity one another in a gun housing, wherein the explosive forces from the explosive ignition means and the explosive forces of the shaped charges themselves otherwise tend to react detrimentally upon each other to impair the penetrating efficiency of the device.

It is a still further object of this invention to provide a shaped explosive charge device having explosive shielding components that are sealed against entrance moisture and retained firmly together in assembled relationship.

The objects of this invention are attained in general by employing an improved shape of explosive charge by employing means for precisely centered initiation ignition of the charge, and by employing means shielding the rear portions of the shaped charge from external explosive forces and for confining and directing more of the explosive forces to the perforating jet.

The objects of this invention are more particularly attained in a shaped explosive charge device for a hollow carrier well perforator including a forward, main charge unit having a compressed body of high explosive material, and a layer of metal covering the rearward portion of the body of high explosive material and providing therethrough a rearward opening, the body providing at the forward end thereof a forwardly opening cavity. The device further includes a rearward booster charge unit having a metallic booster cup having side walls abutting the before-mentioned layer of metal adjacent the opening therein and a thick rear end portion providing a rearward aperture, and a compressed charge of booster material filling the booster cup and being in substantial contact with the rear of the body of high explosive through the opening in the layer of metal. The device still further includes a shell formed from resilient material, the shell providing a forwardly facing hole conforming generally to and, in the relaxed state of the shell, being slightly smaller than the lateral and rearward exterior surfaces of the main charge unit and booster charge unit, the shell being contracted about the lateral and rearward exterior surfaces of the charge unit. The shell provides a fuse hole therethrough adapted to receive a detonating fuse and to position a portion of the fuse rearwardly of the aperture of the booster cup detonating relation to the charge of booster material through the aperture.

Other objects, advantages, and features of novelty the invention will be evident hereinafter.

In the drawings, which illustrate a preferred embodiment of the invention:

Figure 1 is a view, partly in elevation and partly longitudinal section, of a completely assembled perforating apparatus, illustrating a typical arrangement of the shaped charge devices of this invention; and

Figure 2 is a cross-sectional view, on an enlarged scale, taken on line 2—2 of Figure 1, and showing the detailed construction of the shaped charge unit of this invention.

Referring first primarily to Figure 1, typical perforating apparatus adapted to contain the shaped charge unit comprises a housing in the form of a thick walled, elongated, steel tube or cylinder 10 closed at its lower end by suitable means, such as a tapered bull plug 11, and closed and adapted to be supported at its upper end by a cable head 12 which is coupled to the top of the housing through an intermediate sleeve member 13 which may be threaded connection with the cable head 12 and the cylinder 10 through left-hand and right-hand threads 14 and

spectively. A conductor cable 16, containing an lead conductor 17, enters and is anchored within head 12 and serves both as a means for lowering rforator apparatus into the well and for conducting electrical firing impulse to the firing mechanism or therein. Typical cable head construction suitable connection is illustrated in the patent to Turechek 1,043,341. The electrical conductor 17 within the ctor cable 16 may be connected through the cable 12 and through a suitable insulated electric con-

18 to an electric detonating cap 20. The deton- cap 20 is secured within the upper end of a tubular terminal union 21, which is in turn supported cen- within the upper end of the housing 10 by means entrally perforated diaphragm 23. A suitable fuse nich is threaded through the rear end portions of aped charge units, as hereinafter more fully de- 1, enters and is crimped into the lower end of the terminal union 21 adjacent to or in contact with fore-mentioned electric detonator cap 20.

2 thick wall of the housing 10 is provided with a of longitudinally spaced, radially directed openings rts 25 extending between the outside and inside l bore or chamber 26, each port being enlarged outside end by a short counterbore 28 to receive a al disc 27. Such series of ports 25 (only two of are shown in Figure 1, duplicate portions thereof been omitted) may be arranged along the housing any desired pattern. One suitable arrangement or 1 which is frequently used is to place the ports 25 spiral arrangement in the housing.

3 shaped charge unit, such as shown at 30, is adapted mounted opposite each of the ports 25 and pos- so that the jet-shaped blast projected from the for- concave end of the shaped charge will pass through nter of the port. In order to position and acc- maintain each such shaped charge 30 in axial ent with the center of its respective port 25, the vall of the cylindrical gun housing 10, diametrically te each port 25, is provided with suitable means to and support the rear end portion of the shaped unit. Preferably such means takes the form of llly directed, cylindrical recess 32, and the rear end 1 33 of the shaped charge shell is formed to fit such recess 32. The forward end of the shaped unit 30 may be supported by any suitable means d to hold the rear end of the shaped charge 30 y seated within the recess 32 and at the same time in accurate alignment of the axis of the shaped with the center of the port 25. For this purpose, ner, such as best shown at 35 in Figure 2, may be ed. This retainer is in the general form of a hol- uncted cone, with thick end portions 36 and 37 for telescopng engagement within the annular recess ned in the forward end of the shaped charge unit, thin the inside surface of the inner end portion of rt 25, respectively, and a thinner, coaxial, frusto-, tubular, interconnecting portion 39 extending be- these thick end portions. The tubular portion 39 erably of flexible, resilient material, such as rubber, ne, or the like material, to enable one end portion to be collapsed or be telescopcd within the other portion for initial installation of the shaped charge ithin the bore of the housing 10.

4 a more complete description of the retainer 35 operation in connection with the loading of the charges into the housing 10, reference may be had . Patent No. 2,707,917, issued May 10, 1955, on plication of Lindsay and Phillips, Serial No. 7, filed July 25, 1949, which application was co- g with applicant's parent application of which the application is a continuation.

5 rring now principally to Figure 2, in which the unction of the shaped charge of this invention is il- ed in more detail, the explosive charge 45 of this

invention is contained in a shell 46 of varying inside and outside diameter and shape from end to end. The exterior of the shell 46 is formed with a cylindrical forward end portion 47, a rearwardly converging, intermediate portion 48, and a cylindrical rear end extension portion or boss 33 of relatively small diameter as compared to the cylindrical forward portion 47. The cylindrical rear end boss 33 is of such size and shape as to adapt it to be inserted into any one of the hereinbefore-mentioned recesses 32 formed in the inside surface of the wall of the housing 10 diametrically opposite the ports 25, as illus- trated in Figures 1 and 2. The forward end of the shell 46 is provided with the hereinbefore-mentioned annular recess 38 to receive the inner annular end portion 36 of the before-mentioned retainer 35.

6 The exterior surface of the explosive material 45 of the shaped charge fits the interior surface of the shell 46 and is shaped exteriorly with a forward cylindrical zone 50, an intermediate, rearwardly converging, frusto- conical zone 51, an annular shoulder surface 53 lying in a plane normal to the axis of the shaped charge, with the outer circumference thereof joining the rear end of said frusto-conical zone 51, and a rear, cylindrical zone 54 of reduced diameter relative to said forward zone 50 25 extending rearwardly from the inner circumference of said annular shoulder 53.

7 The body of explosive material 45 has formed in the forward end thereof a substantially conical, forwardly facing concavity 56 concentric with the before-mentioned exterior surface zones thereof. The conical concavity 56 is preferably lined with a layer of metal, as shown at 57. This inner layer or conical liner 57 may be made of a suitable non-explosive material preferably having a relatively high density, such as, for example, copper, aluminum, steel, or the like.

8 The exterior surfaces of the portion 45a of the ex- plosive charge 45 at the intermediate, frusto-conical zone 51, and the annular shoulder surface 53, are also covered, as shown at 52, with a relatively thin layer of 40 metal, which may be one of the same materials as em- ployed for the before-mentioned conical liner 57 but usually of less thickness. The exterior surface of the portion 45b of the explosive charge 45 at the rear cy- lindrical zone 54 is also covered with a metal layer, the forward portion of which, as shown at 59, comprises a relatively thin, annular or tubular shaped portion of sub- stantially the same thickness as the layer at 52, and the rear end portion of which comprises a relatively thick, annular closure member 60 provided in the center there- 50 of with a central aperture 61. This central aperture may be closed, if desired, at the outer end by means of a relatively thin diaphragm 62 of metal foil, paper, or other suitable material. The tubular metal portion 54 and end closure member 60 thus containing explosive charge 45b may also be made of copper, steel, or the like material.

51 A bore 63 extends transversely through the rear end boss 33 of the shell 46, through which the detonating fuse, hereinbefore mentioned and illustrated at 24 in Figure 1, may be threaded. The detonating fuse 24 thus positioned lies closely adjacent the aperture 61 and dia- phragm 62 in the end closure member 60 of the rear cy- lindrical zone 54 of the explosive charge. The fuse may be threaded through the bores 63 of the several shaped charge units in the housing, in the manner more fully shown and described in the before-mentioned Lindsay et al. Patent No. 2,707,917.

52 The fuse 24 is of an explosive or detonating type, such as, for example, that known commercially as "P.E.T.N. Reinforced Primacord," designated as "50 gr./ft." The explosive body 45 of the shaped charge contained within the shell 47, as hereinbefore described, is preferably pressed or pelletized in two separate units, the forward or main charge unit 45a being preferably composed of a high explosive, such as "A" RDX (cyclotrimethylenetri-

nitramine), and the rearward unit 45b being preferably composed of pure Cyclonite, which is the trade name of a high explosive manufactured by E. I. du Pont de Nemours and Company. The charge 45b is preferably of a lower density than the main charge 45a and is thus more sensitive, whereby it may serve, in effect, as a booster charge for the main charge.

In the operation of the apparatus, an electric potential is applied to the conductor 17, which is transmitted down through the conductor cable from the top of the bore-hole to the cable head, through conductor 18 within the cable head, and through the electric detonator cap 20 to ground. The resultant detonation of the detonator cap 20 in turn detonates the fuse 24, the explosive wave of which travels throughout its full length from the top to the bottom thereof at a high velocity. Since in each shaped charge unit the explosive fuse 24 extends through the transverse fuse bore 63 in the rear end boss 33 of the shaped charge shell, the explosive force is first applied thereby to the rear end closure member 60. Because of the relatively great thickness and mass of the rear end closure member 60, it offers a very high inertia force opposing the forces resulting from the detonation of the fuse 24, thereby initially permitting only the rupture of the diaphragm 62 and the detonation of the charge 45b contained within the rear cylindrical zone 54 at the central aperture 61. Thus the detonation of the charge 45b is initiated at a relatively small focal point or area at the rear end extremity thereof, accurately positioned on the axis of the shaped charge. The explosive wave thus initiated progresses radially from the aperture 61 as a focal center, forward through the relatively sensitive charge 45b within the rear end cylindrical portion thereof within the tubular container 59, and thence into the rearward central portion of the main charge 45a, in turn collapsing the conical liner 57 and producing a forwardly directed, high velocity jet of gases and metal having high penetrating power. As the detonating wave progresses in the main explosive body 45a into the space between the conical metal liner 57 and the external metal layer or covering at 51 and 53, the weight of the covering at 51 and 53 is such that it offers extremely high inertia to the outward and rearward dissipation of the explosive forces at that point, thereby resisting and retarding the outward dissipation of the explosive energy there and thereby confining a portion thereof to the body of gases which make up the perforating jet. Additionally, the metal covering at zones 51 and 53 and also the metal covering in the rear cylindrical zone 54 serve to shield these rear end portions of the shaped charge explosive material from the pressure waves and explosive forces generated by the adjacent portions of the detonating fuse 24 and neighboring shaped charges. The pattern of detonation of the shaped charge is thus shielded to a substantial and effective degree from external forces which otherwise tend to interfere with the symmetrical progress of the detonating wave from the central point of detonation at the aperture 61 to the forward edge of the cavity 56, and which thus otherwise would tend to distort the jet issuing from the shaped charge in such a manner as to impair its penetrating power. The metal coverings at 51, 53, and 60 thus serve both to shield the shaped charge from the detrimental effects of explosive forces from the adjacent explosive bodies and to confine and cause the explosive forces of the shaped charge to be more efficiently utilized to form the perforating jet.

The shaped charge shell 46 is preferably made of a resilient material, such as rubber or the like material, which serves in addition to being a holder for the shaped charge explosive, as an efficient seal against entrance of moisture, and shields the explosive material against variations in its performance which may be due to weather and temperature change. The resilient shell 46 is preferably made slightly undersize, and the explosive pellets 45a and 45b are pressed in place within it, causing the

case to be expanded slightly, thereby applying a pressure loaded condition diametrically on the pellets, thereby insuring that the pellets and cone will be retained firmly together under varying conditions. The cone liner 57 may have a thickness in the order of .026", and metal coverings at 51, 53, and 54 may have a thickness of the order of approximately .015". The thickness of the rear end closure member 60 may be approximately .093". The aperture 61 in the rear end closure member 60 may have an inside diameter of approximately $\frac{1}{4}$ in. When aperture closure 62 is used, it may be made of metal foil having a thickness of from .002 to .005. These dimensions are suitable for a shaped charge having an axial length of approximately $1\frac{1}{8}$ " from the tubular shoulder 53 to the forward edge of the conical liner 57 and containing approximately 21 grams of RDX explosive material. The angle of the conical liner is dependent somewhat upon the diameter of the housing 10 in which it is to be installed, and may vary as required to obtain an optimum stand-off equal to the distance from the charge to the port seal.

It is to be understood that the foregoing is illustrative only, and that the invention is not limited thereby, it may include various modifications and changes made by those skilled in the art without distinguishing from the scope of the invention as defined in the appended claims.

I claim:

1. A shaped explosive charge device for a hollow carrier well perforator comprising: a forward, main charge unit including a compressed body of high explosive material, a layer of metal covering the rearward portion of said body of high explosive material and providing therethrough a rearward opening, said body providing at its forward end thereof a forwardly opening cavity; a rearward, booster charge unit including a metallic booster cup having side walls abutting said layer of metal adjacent the opening therein and a thick rear end portion providing a rearward aperture, and a compressed charge of booster material filling said booster cup and being in substantial contact with the rear of said body of high explosive through the opening in said layer of metal; a shell formed from resilient material, said shell providing a forwardly facing hollow conforming generally to and, in the relaxed state of said shell, being slightly smaller than the lateral and rearward exterior surfaces of said units, said shell being contracted about the lateral and rearward exterior surfaces of said units, said shell providing a fuse hole therethrough adapted to receive a detonating fuse and to position a portion of the fuse rearwardly of the aperture of said booster cup in detonating relation to said charge of booster material through said aperture.

2. A shaped explosive charge device for a hollow carrier well perforator comprising: a forward, pelletized main charge unit including a compressed body of high explosive material, the external surfaces of which are surfaces of revolution about an axis of symmetry, a layer of metal covering the rearward portion of said body of high explosive and providing therethrough a central, circular axial opening, said body providing at the forward end thereof a substantially conical, forwardly facing coaxial cavity, and a liner seated in said cavity; a rearward, pelletized, booster charge unit including a metallic booster cup symmetrical about said axis having side walls abutting said layer of metal adjacent the periphery of said circular opening and a thick rear end portion providing an axial central aperture of reduced diameter, and a compressed charge of booster material filling said booster cup and being in substantial contact with the rear of said body of high explosive through the circular opening in said layer of metal; and a coaxial shell formed from resilient material, such as rubber and the like, said shell providing a forwardly facing hollow conforming generally to and, in the relaxed state of said shell, being slightly smaller than the laterally and rear-

facing exterior surfaces of said said units, said shell contracted about the laterally and rearwardly exterior surfaces of said units to retain the latter together, said shell providing a transverse hole rough rearwardly of said booster cup adapted to a detonating fuse and to position a portion of the rearwardly of the aperture of said booster cup in fitting relation to said booster explosive material in said aperture.

3. A shaped explosive charge device for a hollow carrier perforator comprising: a forward, pelletized, charge unit including a compressed body of high density material having a forward cylindrical outer surface merging at the rear into a coaxial, rearwardly flaring, frusto-conical surface merging at the rear into a coaxial, annular shoulder surface lying in a plane parallel to the axis of the cylindrical outer surface of said body, a layer of metal covering said frusto-conical surface and said annular shoulder surface and providing an opening extending radially inwardly from said outer surface, said body providing in the forward end a substantially conical, forwardly facing, coaxial cavity, and a liner seated in said concavity; a rear-pelletized, booster charge unit including a forward-facing, cylindrical, metallic booster cup having cylindrical side walls abutting said layer of metal at the inner central opening thereof, the side walls of said cup being of substantially the same thickness as the layer of metal, said booster cup having a rear end substantially thicker than said layer of metal and an axial central aperture of reduced diameter,

5

10

15

20

25

30

and a compressed charge of booster explosive material filling said booster cup and being in substantial contact with the rear of said body of high explosive through the central opening in said layer of metal; and a coaxial shell formed from resilient material, such as rubber and the like, said shell providing a forwardly facing hollow conforming generally to and, in the relaxed state of said shell, being slightly smaller than the laterally and rearwardly facing exterior surfaces of said units, said shell being contracted about the laterally and rearwardly facing exterior surfaces of said units to retain the latter firmly together, said shell providing a transverse hole therethrough rearwardly of said booster cup adapted to receive a detonating fuse and to position a portion of the fuse rearwardly of the aperture of said booster cup in detonating relation to said booster explosive material through said aperture.

4. A shaped explosive charge device for a hollow carrier well perforator as defined in claim 3 wherein: said liner has its forward periphery in contact with the wall of the hollow of said shell, and said shell is contracted about said periphery of said liner to seal said explosive material from external atmospheric influences.
